FLAT KNITTING MACHINE

Joseph Haines, Jr., Meadowbrook, Pa., assignor
to Haines Hosiery Mills, Inc., Philadelphia,
Pa., a corporation of Pennsylvania

Application December 13, 1934, Serial No. 757,273

6 Claims. (Cl. 66—82)

This invention relates to flat knitting machines; and especially to flat knitting machines of the "Cotton" type ordinarily used in the manufacture of full fashioned stockings, including both 5 "leggers" on which the leg blanks are produced, and "footers" to which the leg blanks are transferred for the formation of stocking feet as direct continuations of said blanks.

In flat knitting machines of the kind with which 10 my invention is particularly concerned, the various sub-mechanisms necessary in the production of fashioned articles like stocking leg blanks and stocking feet, are motivated from a longitudinally-extending cam shaft (which I will hereinafter term the "main" shaft), and the order 15 of their performance is determined, through suitable interposed connections, by a timing chain. While the timing chain satisfactorily served the purposes for which it was designed in the conventional form of flat knitting machine wherein 20 many of the settings and adjustments were manually effected, the advent of means, such as disclosed in U. S. Patents Nos. 1,850,520; 1,851,209; 1,826,660; and 1,822,169, distributed at different 25 points along the machine for effecting the aforementioned settings and adjustments automatically, gave rise to the need for a more flexible timing means capable of determining the sequential performance of the various sub-mechanisms of the machine with greater accuracy and 30 precision than possible of attainment with the timing chain alone.

In the main, my invention is directed toward fulfilling the above noted deficiency. This object 35 I realize in practice, as hereinafter more fully disclosed, through provision of an auxiliary shaft extending lengthwise of the machine in parallelism with the main shaft, and having actuating instrumentalities thereon in proximity to the respective parts or mechanisms which are to be 40 operated or controlled.

A further aim of my invention is to provide 45 simple and reliable means whereby the auxiliary shaft is intermittently racked under governance of the usual timing chain of the knitting machine through motion derived from the main shaft, with determination of operative phases of the control instrumentalities on said shaft during which the sub-mechanisms of the machine are caused to 50 perform their allotted functions in proper sequence for the production of complete stocking blanks. The chain may thus be broadly regarded as a "primary" timing means, and the auxiliary shaft as a "secondary" timing means, and they 55

will be so referred to in certain of the claims hereunto annexed.

From the detailed description which follows, it will be apparent that my invention is adaptable with attainment of the foregoing advantages, to 5 "leggers" and "footers", as well as to single unit full fashioned stocking machines.

In the drawings, Figs. I and Ia, taken together, show the rear elevation of a flat knitting machine embodying my invention.

Fig. II is a cross section of the machine taken as indicated by the arrows II—II in Fig. Ia.

Fig. III is a fragmentary detail illustration viewed as indicated by the arrows III—III in Fig. II.

Fig. IV is a fragmentary detail illustration viewed as indicated by the arrows IV—IV in Fig. II; and

Fig. V is a detail section taken as indicated by the arrows V—V in Fig. IV.

Fig. VI is a fragmentary view partly in elevation and partly in section taken as indicated by the arrows VI—VI in Fig. I.

Fig. VIII is a detail section taken as indicated by the arrows VIII—VIII in Fig. VI.

Fig. IX is a fragmentary cross section of the machine taken as indicated by the arrows IX—IX in Fig. I.

Fig. X is a fragmentary view looking as indicated by the arrows X—X in Fig. IX.

Fig. XI is a detail section taken as indicated by the arrows XI—XI in Fig. X.

Fig. XII is a fragmentary view looking as indicated by the arrows XII—XII in Fig. IX.

Fig. XIII is a fragmentary cross sectional view of the machine taken as indicated by the arrows XIII—XIII in Fig. Ia.

Fig. XIV is a view looking as indicated by the arrows XIV—XIV in Fig. XIII.

Fig. XV is a fragmentary cross section of the machine taken as indicated by the arrows XV—XV in Fig. Ia.

Fig. XVI is a view looking as indicated by the arrows XVI—XVI in Fig. XV; and

Fig. XVII is a fragmentary perspective view showing one of the needle bars of the machine and the parts for controlling the size of the loops formed by the needles.

The flat knitting machine chosen for the purposes of illustration herein is of the "Cotton" type such as is ordinarily used in the production of full fashioned hosiery, and generally speaking, said machine is of standard or conventional con-

5

10

15

20

30

35

40

45

50

55

struction, comprising a plurality of serially-arranged knitting sections 1 in the intervals between spaced transverse frames 2 which are connected by longitudinals 3, 4 and 5, each of said 5 knitting sections including a bar 6 with two sets of needles 7 for knitting as many individual stocking fabrics. After customary practice, the machine is provided with several endwise-reciprocatative yarn carrier rods 8 which are slidably 10 guided in fixed brackets 9 on the machine framework, and to each of which are secured pendant carrier fingers 10 whereby yarns are fed to the needles of the several knitting sections 1. The friction box rod of the machine, indicated at 15 11, has mounted thereon a series of friction boxes 12, one for each yarn carrier rod. These friction boxes 12 are of a type having upper and lower friction shoes 13 bearing against the friction box rod 11, and leaf springs 14 adapted, when 20 compressed, to exert pressure upon said shoes and thereby cause the box to travel along with said rod, each friction box being moreover provided as ordinarily, with a slide bolt 15 for connection to one of the carrier bars 8. The means 25 for reciprocating the friction box rod 11 may be of known construction and has not been illustrated. Also after common practice, the needle bars 6 are pivotally supported at the ends of horizontal arms 16 which reach inwardly from a longitudinal shaft 17 at the upper frontal portion of 30 the machine. The shaft 17 is journaled in suitable bearings on the cross frames 2, and rocked by coaction of a pendant roller arm 18 thereon with a rotary cam on the main shaft 19, whereby 35 the needles 7 are moved up and down relative to the sinkers 20 and the knockovers 21 during the formation of fabric loops from yarns fed as aforesaid. Incident to their up and down movement, the needle bars 6 are swung on their pivotal connections with the arms 16 so that the beards of the needles 7 are closed by pressure against the beard closing ledge at 22 in Fig. II. This pressing movement is obtained in each knitting section 1 through cooperation of a rotary press cam 23 40 on the main shaft 19 with a roller 24 at the end of an arm 25 fast on a second longitudinal rock shaft 26 alongside the rock shaft 17, said arm 25 being releasably coupled, by means of a latch link 27, with an arm 28 pendant from said needle bar. 45 The shifting of the yarn carrier rods 8 is variously limited by end stops 29 (Figs. I and Ia) which are shifted under the influence of the usual screw-actuated narrowing heads 30 at opposite ends of the machine. Furthermore, as customary, the machine is fitted with an endless timing chain 50 31 which is trained about end sprockets 32 and 33 to travel horizontally along the front of the machine, and which is intermittently progressed by suitable means, not shown, in the usual manner. 55 60 For the purpose of directly controlling the various mechanisms of the machine, I have provided a secondary timing means in the form of an auxiliary shaft 34 which extends longitudinally of the back of the machine from one end thereof to the other in parallel relation to the main shaft 19, it being journaled at intervals in bearings 35 on the machine framework. Variously allocated on the auxiliary shaft 34 in proximity to the respective parts or mechanisms which are to be timed, are control instrumentalities having, in this instance, the form of rotary cams 36, 37, 38, 39, 40 and 41 which will be further referred to later. Intermittent rotative movement is imparted to the auxiliary shaft 34 through picking 70 of a ratchet wheel 42 thereon by a pawl 43 on an

arm 44 which is free on said shaft, and which is oscillated by virtue of being coordinated with the rod of an eccentric 45 on the main shaft 19. The racking of the auxiliary shaft 34 is however subject to governance by the timing chain 31, which is fitted with a series of spaced lugs 46 adapted to successively actuate a finger 47 at one end of a transverse shaft 48 journaled in bearings 49 on the framework longitudinals 4 and 5. An arm 50 at the other end of the transverse shaft 48 is coupled, by a vertical link 51, with the arm 52 of a sectoral pawl guard 53, which latter is free on the auxiliary shaft 34 and positioned intermediate the pawl arm 44 and the ratchet wheel 42. Thus, as each of the chain lugs 46 passes the finger 47, the sectoral pawl guard 53 is swung clockwise in Fig. II to permit picking, each time, of one tooth of the ratchet wheel 42, with attendant impartation of rotative movement to a corresponding extent to the auxiliary shaft 34. In the present instance, the chain 31 is provided with as many lugs 46 as there are teeth on the ratchet wheel 42 so that the auxiliary shaft 34 is turned through a full revolution to predetermine a complete knitting cycle of the machine in 25 a manner later on explained. It is to be understood that the machine is provided with fashioning mechanism, automatic stop mechanism, etc., which are subject to the chain 31. These mechanisms may all be of the well known conventional forms and have been omitted from the drawings to avoid complicity of illustration.

The cams 36 on the auxiliary shaft 34, I utilize, for example, to control selection as between the several yarn carriers 10 by actuation of the friction boxes 12 associated respectively with said rods, through duplicated interposed means comprehensively indicated respectively by the numeral 54 in Fig. I. As shown in Fig. II, each of the means 54 includes a bell crank lever 55 which is fulcrumed on a fixed bracket of the machine framework, and which, on its short extremity, carries a roller 56 that engages a side face cam groove in the corresponding cam 36 on the auxiliary shaft 34. The longer extremity 45 of the bell crank lever 55, on the other hand, is pivotally connected to the lower end of a vertically-reciprocatative bar 57 whereof the upper end is slidably guided in a yoke member 58 free on a section 59a of a divided shaft 59 extending 50 horizontally of the machine adjacent the friction box rod 11. From Fig. II it will be observed that the bar 57 is formed at its upper end with a toothed rack 60 which meshes with a spur pinion 61 on the corresponding section 55 59a of the shaft 59. Splined to the shaft section 59a with capacity to slide endwise thereon, is a sleeve 62 having at one end, a miter pinion 63 that meshes with a companion miter pinion 64 whereof the axis member 65 is journaled in 60 bearing lugs 66 on the friction box 12, see Figs. III and IV. Secured to the axis member 65 is a disk cam 67 with a flattened face 67a bearing on the leaf spring 14. As shown in Fig. IV, the sleeve 62 has a circumferential groove 68 embraced by a lateral bracket piece 69 on the friction box rod 11 for movement with the friction box 12; and secured to said bracket piece is a plate 70 with a downwardly bent portion 70a adapted to normally overreach a circumferential 70 projection 71 on a collar 72 secured to the shaft section 59a. The sleeve 62, it will be observed from Figs. II-IV has an integral arm 73, which, by means of a link 74 is coupled with the slide bolt 15 of the friction box 12. With this ar- 75

angement, it will be seen, that as the rotary cam 36 is revolved, the radial offset 36a of its side groove will cause actuation of the bell crank lever 55 with attendant lifting of the bar 57 whereby the shaft section 59a will be turned clockwise in Fig. II through a part rotation. The movement thus induced in the shaft section 59a will be communicated, by the bevel gear pinions 63 and 64, to the disk cam 67 with incidental compression of the leaf spring 14 and pressure coupling of the friction box 12 with the friction box rod 11, as well as shifting of the slide bolt 15 of the friction box into engagement with the notched projection 75 (Fig. III) on a predetermined carrier rod 8. Accordingly, as the friction box rod 11 is shifted, the friction box 12 and the corresponding yarn carrier rod 8 will follow suit and feed yarns to the needles 7 of the several knitting sections 1. It is to be understood in this connection that the rotary cams 36 are placed in different angular positions on the auxiliary shaft 34 so that the yarn carrier rods 8 will be selectively operated as desired. The function of the plate 70 and the cooperating projection 71 on the collar 72 is to normally hold the friction box 12 against accidental movement with the friction box rod 11. However, when the shaft section 59a is turned as above explained, the projection 71 of the collar 72 will be rotatively advanced beyond the province of the downturned end 70a of the plate 70, so that the friction box 12 is permitted to follow the dictates of the friction box rod 11. Per se, the yarn carrier selecting mechanism above described forms no part of the present invention, it being fully covered in U. S. Patent No. 1,850,520 hereinbefore referred to.

The rotary cams 37 on the auxiliary shaft 34, I employ to respectively control automatic means 76 (Figs. I and Ia) for selectively actuating the duplicate sets of end stops 29 for the yarn carriers 8, one of such mechanisms being shown in detail in Figs. VI and VIII. As usual, the end stops 29 are in each case mounted for independent swinging movement on a pivotal axis 78 carried by the screw-actuated follower nut 79 of the narrowing head 30 at the corresponding end of the machine. Each of the automatic means 76 comprises a shaft 81 which is journaled in supplemental bearing arms 79a on the follower nut 79 of the narrowing head 30. Secured to the shaft 81 by means of screws 82, are collars 83 in alignment with certain of the stops 29 which are to be actuated. The heads of the screws 82 serve as circumferential projections of the collars 83 for engaging circumferentially adjustable peripheral lugs 84 on the bosses of the corresponding stops 29, thereby to swing said stops upward to inactive position shown in dot and dash lines in Fig. VIII when the axis 78 is turned. To the end of the shaft 81 is affixed a spur gear 85 which meshes with a spur gear 86 free on a stud 87 projecting from the follower nut 79. A miter pinion 88 secured to the gear 86 meshes with a miter pinion 89 on a longitudinal shaft 90 having journal support in outwardly reaching bearing arms 91 of fixed brackets 92 on the machine framework. The pinion 89 is keyed to the shaft 90 with capacity to slide therewith, in following the movements of the nut 79, which latter has a forked projection engaging a circumferential groove 95 in the hub of said pinion, see Fig. VII. Secured to the shaft 90 is a ratchet wheel 96 which is arranged to be intermittently picked by a spring-influ-

enced pawl 97 on a lever 98 free on said shaft. As shown, the lever 98 is coupled, by means of a downward link 99, with the longer extremity of a bell crank lever 100 fulcrumed at 101 to a fixed bracket 102 on the longitudinal 5 of the machine framework. The shorter arm of the bell crank lever 100 (Fig. VI) carries a roller 103 which engages the side face groove 37a of the rotary cam 37 on the auxiliary shaft 34. The groove 37a of the cam 37, it will be noted, has several circumferential rises 37b which are instrumental in rocking the bell crank lever 100, and through the previously described connections, picking of a tooth of the ratchet wheel 96 on the shaft 90 at each actuation. The motion thus induced in the shaft 90 is transmitted, by the bevel gears 88 and 89 and spur gears 85 and 86 to the shaft 81 on the follower nut 79 carrying the drum collars 83 for actuating the swingable end stops 29 for the yarn carrier rods 8. In practice, the collars 83 are set upon the shaft 81 such that the projecting heads of the securing screws 82 are variously positioned circumferentially to predetermined successive actuation of the end stops 29 in any desired sequence. The above described end stop control mechanism corresponds to that featured in Patent No. 1,851,209 hereinbefore referred to.

The rotary cam 38 on the auxiliary shaft 34, I utilize for controlling the operation of a high heel splicing or plating mechanism which is comprehensively designated by the numeral 105. This mechanism is located about midway of the length of the machine as shown in Fig. I, and is illustrated in detail in Figs. IX, X, XI and XII. As shown, the mechanism 105 comprises a pair of ratchet wheels 106 and 107 which are supported, for independent rotation by a fixed bracket 108 on the machine framework. On their outer sides the ratchet wheels 106 and 107 have stepped annular flanges 109 and 110 respectively which constitute variable abutments for stop screws 111 and 112 on the two rods 8a and 8b for the carriers 10a and 10b which serve splicing or plating yarns to the needles 7 incident to the knitting of the high heel reinforces of the stocking blanks B, (Fig. XII). The ratchet wheels 106 and 107 are adapted to be independently rotated clockwise in Fig. IX by pawls 113 and 114 respectively, said pawls being pivotally connected to levers 115 and 116 fulcrumed for independent swinging movement on a shaft 117 in the bracket 108. At their lower ends the arms 115 and 116 are provided with adjustable stud projections 118 and 119 to cooperate with cam blocks 120 and 121 on the slur cock bar 122 of the knitting machine. Thus, as the slur cock bar 122 moves in one direction the cam block 120 will actuate the pawl arm 115, and when said bar moves in the opposite direction, the cam block 121 will actuate the pawl arm 116. Accordingly, during each complete reciprocation of the slur cock bar 122, the ratchet wheels 106 and 107 are successively moved to the extent of one tooth, thereby bringing the different steps of their annular flanges 109 and 110 into position to be engaged by the stop screws 111 and 112 on the yarn carrier rods 8a and 8b for the purposes of tapering or otherwise giving the high heel splicing an ornamental configuration. Secured to opposite ends of the shaft 117 are levers 125 and 126, whereof the ends are connected by a cross bar 127 which underlies the pawls 113 and 114. As shown in Fig. IX the arm 126 has a horizontal extremity 126a which is coupled, 75

by means of a vertical link 128, with the horizontal arm 129a of a bell crank lever 129 fulcrumed on a fixed bracket 130 of the machine framework, see Figs. I and IX, the vertical arm 129b of said bell crank lever carrying a roller 131 to cooperate with the cam 38 on the auxiliary shaft 34. A coiled spring 132 serves to maintain the roller 131 in yielding contact with the cam 38. From Fig. IX it will be observed that the cam 38 has two lateral rises 38a and 38b. With the cam 38 resting in the position of Fig. IX and the roller 131 in engagement with the rise 38a, the pawls 113 and 114 will be permitted to pick the ratchet wheels 106 and 107 through a circumferential extent corresponding to that of the stepped flanges 109 and 110 of said ratchet wheels incident to formation of the high heel areas. When the roller 131 rests upon the blank portions of the cam 38, the arms 125 and 126 are retracted and the pawls 113 and 114 held away from the ratchet wheels 106 and 107 by the cross bar 127. When the cam 38 on the auxiliary shaft 34 is advanced so that the lateral projection 38b thereof engages the roller 131, the pawls 113 and 114 will be permitted to complete the racking cycle of the ratchet wheels 106 and 107 and thereby restore the mechanism 105 to starting position.

The cam 39 on the auxiliary shaft 34 serves to govern the functioning of means 135 for controlling the length of the fabric loops, this means being shown in detail in Figs. XIII, XIV and XVII. The usual loop regulating shaft of the knitting machine is indicated at 136 in Figs. XIII and XVII, the same having secured to it a finger 137 which operates as a stop for the arm 25, thereby to limit the approach of the roller 24 on said arm with the press cam 23 on the main cam shaft 19 of the machine and thereby correspondingly limit the inward movement of the needles 7 in predetermining fabric loops of normal size. The usual loop regulating lever is indicated at 138. The bifurcated component 138a of the loop regulating lever 138 is free on the shaft 136 and carries a roller 139 which cooperates with another cam 140 on the main shaft 19. As shown in Fig. XIII, the roller 139 revolves on an axis pin 141 having eccentric ends engaged in the bifurcations of the lever component 138a. The other component 138b of the regulating lever 138 is secured to a shaft by set screws, and is subject to a tension spring 142. This spring 142 acts to maintain a master adjusting screw 143 in the lever component 138b in contact with the lever component 138a, and in turn to maintain the roller 139 of the latter component in engagement with the cam 140. Affixed to one end of the axis pin 141 of the roller 139 on the regulating lever component 138a is a bevel pinion 145 which meshes with the larger bevel gear wheel 146. This gear wheel 146 is secured to the upper end of a shaft 147 which is journaled in a bearing 148 at the end of a rod 149 reaching from one side of the regulating lever component 138a. An arm 150 at the lower end of the shaft 147 is fitted with a pair of rollers 151 and 152 whereof the upper one is arranged to contact with a lateral segmental wing cam 153 of an oscillating collar 154 engaged between spaced circumferential ridges 155 and 156 of a sleeve 157 free on the shaft 136. As shown in Fig. XIV, the sleeve 157 is held against displacement through abutment of one of its ends with the boss of the regulating lever component 138b, and 75 of its other end with a collar 158 fast on the

shaft 136. A third circumferential ridge 159, at the right hand end of the sleeve 157, has peripheral notches occupied by adjustable stops 160 which are adapted to coact with the lowermost roller 152 on the arm 150. A spring 161 connected at one end to the arm 138a, and at the other to the bevel gear 146, serves to yieldingly urge the roller arm 149 toward the stops 160 on the sleeve 157. By means of a pawl 162, the sleeve 157 is intermittently rotated so that the stops 160 are successively presented to the lower roller 152 on the arm 150. The pawl is pivoted on a stud let into the side of the cam wing 153, and arranged to pick ratchet teeth on the circumferential ridge 155 of the sleeve, said ratchet teeth corresponding in number to the stops 160. The pawl 162 is actuated by the cam 39 on the auxiliary shaft 34 through means including a lever 163 with a roller 165 at one end thereof engaging the side groove 39a in said cam, said groove having a number of circumferential rises 39b. As shown, the lever 163 is fulcrumed, at a point intermediate its ends, on a bracket 166 secured to the longitudinal 5 of the machine framework, and its lower end is coupled, by means of a link 167, with a motion-transmitting rocker arm 168 free on a shaft 169 which is suitably supported between certain of the transverse frames 2 of the machine framework. The upper extremity of the rocker arm 168 is in turn coordinated, through a link 170, with the stud 162a on which the pawl 162 is pivoted. During the rotative movement of the cam 39 on the auxiliary shaft 34, each of its circumferential rises 39b causes the ratchet wheel 155 to be picked one tooth. The function of the cam wing 153 is to swing the roller arm 150 clear of the stops 160, thereby to enable stepping about of the sleeve 157 by the pawl 162 incident to substitution of one stop for another. Such movement of the arm 150 is of course attended initially by rotation of the gear wheel 146 in one direction; but as the cam wing 153 returns to the normal illustrated position, the spring 161 induces counter rotation of the gear wheel, which movement is limited by engagement of the arm 150 with the newly presented stop 160. As a consequence of its coordination with the arm 150 through the gears 145 and 146, the eccentric axis 141 of the roller 139 on the regulating lever component 138a is rotated each time to a different angular position from that previously occupied, so that the loop regulating shaft 136 is swung through a corresponding angle with predetermination of larger or smaller loops by the knitting instrumentalities of the machine in the known manner.

The cam 40 on the auxiliary cam shaft 34, I utilize for controlling the functioning of the means (Figs. XV-XVII) on the machine for determining loose courses, as may be required in different points in the knitting of the stockings, for example, at the initiation of a new set, or crosswise of the heel tabs. Ordinarily, such loose course means is caused to function by swinging of a hand lever 172 and resultant shifting of a roller 173 of an arm 175 affixed to the loop regulating shaft 136 into the province of a rotary cam 176 on the main shaft 19. This shifting is effected automatically in the present instance through the medium of a lever 177 which is fulcrumed intermediate its ends, at 178, on a bracket 179 secured to the longitudinal 5 of the machine framework, said arm carrying a roller 180 adapted to cooperate with the side of the cam 40 75

on the auxiliary shaft 34, which cam, as shown in Fig. XVI is provided with one or more lateral projections 40a as may be required.

The cam 41 on the auxiliary shaft 34 serves to automatically control the split slack means on the machine (Figs. XV-XVII) which determines the formation of larger stitches in portions of each course of the knitting, as for example, incident to the high heel splicing. Ordinarily, this is effected by manual shifting of the roller 181 of an arm 182 on the stitch regulating shaft 136 into the province of the double lobed cam 183 on the main cam shaft 19 by means of a hand lever 184. In the present instance such shifting is accomplished automatically through means including a lever 185 which is similar to the lever 177 already described, and fulcrumed at 186 to another bracket 187 on the longitudinal 5 of the machine framework, said lever 185 being provided with a roller 188 within the range of a lateral projection 41a of the cam 41 on the auxiliary shaft.

The loose course and split slack means just described, per se, constitute the subject matter 25 of U. S. Patent No. 1,822,169 hereinbefore referred to.

In practice, the cams 36-41 are preferably so designed and so set on the auxiliary shaft 34 as to determine, during each rotative phase of said shaft under the dictates of the timing chain 31, a knitting cycle incident to which the different sub-mechanisms of the machine, to wit: the yarn carrier selecting mechanism, the yarn carrier end stop mechanism, the heel reinforce control 35 mechanism, the loop length regulating mechanism, the loose course mechanism, and the split slack mechanism, are caused to function automatically in the proper sequence for the production of a set of complete stocking blanks. In 40 this connection, it is to be understood that any well known means may be used for automatically stopping the machine after the knitting of an initial course to enable application of the welt bars, after the welt fabric has been knitted to 45 permit turning and closing of the welt, and after the completion of each set of blanks.

Obviously additional cams may be provided on the auxiliary cam shaft 34 for controlling parts or mechanisms other than those herein shown 50 and described by way of examples. Among such other mechanisms may be included automatic back-racking means such as featured in a co-pending application Serial No. 409,197, filed on November 23, 1929, by Wilbur I. Tebo, and yarn 55 carrier stop block control means such as featured in U. S. Patent No. 1,881,373.

While I have particularly illustrated and described my invention with relation to a full fashioned "legger", it will be apparent to those skilled 60 in the art that its embodiment in full fashioned "footers" will be attended by advantages equal in all respects to those which have been pointed out elsewhere herein.

Having thus described my invention, I claim:

65 1. A multi-section flat knitting machine comprising a plurality of mechanisms which cooperate to simultaneously produce a plurality of fabric blanks, including yarn carrier mechanism and loop length determining mechanisms 70 differently allocated along the machine, and a loop regulating shaft from which said loop length mechanisms are operated; a main shaft from which all of the mechanisms are actuated; separate timing devices directly associated with all 75 of the mechanisms and positioned in accordance

with the allocation of the mechanisms; and a continuous auxiliary rotary shaft connecting said timing devices and adapted to operate the same in a predetermined sequence during each knitting cycle of the machine.

2. A multi-section flat knitting machine comprising a plurality of mechanisms which cooperate to simultaneously produce a plurality of fabric blanks, including yarn carrier mechanism common to the machine sections and loop length 10 determining mechanisms individual to the machine sections and a loop regulating shaft from which said loop length determining mechanisms are operated; means for actuating all of said mechanisms; separate timing devices directly associated with all of the mechanisms; and a continuous rotary shaft common to said individual timing devices for operating the same to control the actuation of the mechanisms by the actuating means.

3. A multi-section flat knitting machine comprising a plurality of mechanisms which cooperate to simultaneously produce a plurality of fabric blanks including yarn carrier mechanism common to the machine sections and loop length 25 determining mechanisms individual to the machine sections, and a loop regulating shaft from which said loop length determining mechanisms are operated; means for actuating all of said mechanisms; a primary timing means; and an auxiliary timing means controlled by the primary timing means including separate timing devices directly associated with all of the mechanisms, and a continuous rotary shaft common to said individual timing devices for operating the same 30 to control the actuation of the mechanisms by the actuating means.

4. A flat multi-section full-fashioned knitting machine comprising a plurality of mechanisms which cooperate to simultaneously produce a plurality of similar stocking blanks, including yarn carrier mechanism common to the machine sections and loop length 40 determining mechanisms individual to the machine sections, and a loop regulating shaft from which said loop length 45 determining mechanisms are operated; means including a main cam shaft for actuating all of said mechanisms; separate timing cams directly associated with all of the mechanisms; a continuous auxiliary shaft carrying said cams; and means 50 whereby the auxiliary cam shaft is operated from the main cam shaft.

5. A flat multi-section full-fashioned knitting machine comprising a plurality of mechanisms which cooperate to simultaneously produce a plurality of similar stocking blanks, including yarn carrier mechanism common to the machine sections and loop length determining mechanisms individual to the machine sections, and a loop regulating shaft from which said loop length 60 determining mechanisms are operated; means for actuating all of said mechanisms including a main longitudinal shaft; a main timing means including a chain; separate rotary timing devices directly associated with all of the mechanisms; 65 a continuous auxiliary longitudinal shaft connecting the rotary timing devices; and coordinating means whereby said auxiliary shaft is operated from the main shaft under control of the chain.

6. A flat multi-section full-fashioned knitting 70 machine comprising a plurality of mechanisms which cooperate to simultaneously produce a plurality of stocking blanks including yarn carrier mechanism common to the machine sections and loop length determining mechanisms individual 75

to the machine sections, and a loop regulating shaft from which said loop length determining mechanisms are operated; a main longitudinal shaft for actuating all of the mechanisms; a main timing means including a chain; separate rotary timing devices directly associated with all of the mechanisms; a continuous longitudinal auxiliary shaft common to said rotary timing devices; and

means whereby the auxiliary shaft is intermittently actuated and turned through a complete rotation during each cycle of the knitting machine under the control of the chain to effect operation of the mechanisms in a definite sequence during the cycle. 5

JOSEPH HAINES, JR.
